UNITED STATES PATENT OFFICE.

CHARLES N. MOORE, OF DOUGLAS, ARIZONA.

OIL-BURNER.

1,089,855.

Specification of Letters Patent. Patented Mar. 10, 1914.

Application filed April 29, 1913. Serial No. 764,334.

To all whom it may concern:

Be it known that I, CHARLES N. MOORE, a citizen of the United States, residing at Douglas, in the county of Cochise and State of Arizona, have invented new and useful improvements in Oil-Burners, of which the following is a specification.

This invention relates to oil burners.

The object of the present invention is to provide an oil burner particularly designed to thoroughly intermix a fluid fuel and a fluid atomizing agent to obtain the maximum efficiency of combustion by utilizing the minimum component of the fuel medium.

Another object of the invention is to provide an oil burner involving a means agitated by the force of the moving fluids in the burner, whereby the heavy components and other substances carried by the mixed fluids and which ordinarily collect in burners of the liquid burning type will be thoroughly ground and comminuted to such a state that they will readily be discharged from the burner with the moving fluids as a vehicle.

A further object of the invention is to provide an oil burner which is constructed almost entirely of standard pipe fittings, some of which are very slightly altered to combine and operate with the other elements of the burner to produce the desired structure and effect.

The invention consists of the parts and the construction and combination of parts as hereinafter more fully described and claimed, having reference to the accompanying drawings, in which—

Figure 1 is a side elevation of an oil feeding pipe system with the burner attached and the latter in longitudinal central section. Fig. 2 is a side elevation of the burner tip in partial section, showing the fluid director in elevation. Fig. 3 is an end view of the same, showing the fluid director in end view.

In its illustrated embodiment my invention comprises a central, tubular body portion 2 which may be a standard pipe nipple, upon the opposite ends of which are screwed reducers 3 and 4. The reducer 3 is adapted for connection to a pipe or conductor 5, to which is shown connected a T 6, from the vertical branch of which extends a fluid fuel supply pipe 7, and to the rear end of which is connected a supply pipe 8 for an atomizing medium, such as steam or air

under pressure; the fluid fuel and the atomizing agent meeting in the supply pipe 5 and passing therethrough into the adjacent head or reducer 3 of the burner.

In the head end of the burner body 2 there is removably fitted a chambered plug 9, which may be formed from a standard pipe reducer, into the larger threaded end of which is inserted a plug 10 and into the smaller or reduced portion of the chamber 9 may be fitted a smaller plug 11. Between the two plugs of the reducer or chamber 9 there is contained and freely movable a ball 12 of steel or other suitable material which is adapted to be constantly agitated in the cavity of the chamber or reducer 9 during the operation of the burner. For the purpose of agitating this ball 12 I prefer to cut the exterior of the larger plug 10, in the head end of the body 2, with slots or channels 13 arranged at an inclination in the periphery of the plug 10 to its axis so that the mixed fluid fuel and the atomizing agent, such as air or steam, will pass through the channels or slots 13 into the cavity of the reducer 9. The swirling motion of the moving fluid causes the ball 12 to roll around and backwardly and forwardly between the plugs 10 and 11, thus thoroughly dislodging such accretions as may form in or adhere to the inner surface of the chamber or reducer 9 and particularly grinding up such hard substances as may be conveyed therewith by the moving fluids which continue their passage under pressure from the interior of the reducer 9 through discharge apertures 14, a suitable number of which is provided at the shoulder 15 of the chamber or reducer 9, thence issuing into the body 2 of the burner and passing therefrom toward the discharge end of the latter. For further causing the intermingling and mixing of the vaporizing agent and the fluid fuel, such as gas or oil, the reducer or tip 4 of the burner is provided at its inner end with a plug 16. The plug 16 is provided with a series of external channels or slots 17 arranged at an angle to the axis of the plug or substantially spirally. The moving fluid passes from the body 2 of the burner through the channels or slots 17 into the chamber 18 of the reducer 4, in which is freely movable a ball 19, which is here shown as of considerably larger size than the initial grinding ball 12 in the head of the burner. The outer end of the reducer

or discharge tip 4 is closed by a plug 20 which may be removed to permit the insertion and removal of a ball 19, when necessary, to supply renewals. The tip or reducer 4 of the burner is provided with a plurality of outwardly diverging kerfs or discharge apertures 21, of which a suitable number may be provided and at desired positions at the reducing portion 22 of the reducer or tip 4.

In operation, the fluid fuel, such as gas or oil, may be admitted from the pipe 7 into the common conductor 5 and a supply of atomizing medium also forming a vehicle may be admitted from the supply pipe 8; the atomizing medium and fuel passing from the pipe 5 about the plug 10 by flowing through the inclined channels 13. These give the mixture a swirling motion in the cavity of the reducer or chamber 9 causing the ball to be highly agitated and moving with considerable force within the reducer 9 so as to constantly scour the walls of the same to dislodge sticky substances therefrom, and further having the function of grinding such hard or solid substances as may be carried in the fuel so that the substances can be freely conveyed through the discharge apertures 14 of the initial grinding part of the burner into the body 2 of the burner, through which the moving fluid will pass, under pressure, through the channels or slots 17 of the second plug 16 in the burner. Here the mixture will be subjected to a further mixing and grinding action of the larger ball 19 at the tip end of the burner. The mixture passes through the discharge mouths 21 of the tip 4 of the burner where the fuel will be intimately subjected to mixture and contact with oxygen in the air about the tip of the burner and thoroughly consumed by combustion when ignited.

Actual operations with a burner of this type have shown that a minimum quantity of oil or fluid fuel may be thoroughly consumed, when mixed with an atomizing agent or medium and discharged at the tip of the burner into the presence of oxygen, thus producing an economical consumption of fuel in proportion to the heat units developed. This is the result of the thorough intermingling of the atomizing agent and the fuel within the burner by means of the movable agitating devices which not only

serve to increase the degree of mixture, but also serve to destroy thick, gummy quantities of the fuel passing through the burner and grind the hard or solid particles therein, thus enabling their more perfect combustion and further tending to keep the interior of the burner clean by the scouring action and eliminating the necessity of frequently dismounting the burner for the simple purpose of cleaning its interior of accretions and solid deposits.

Having thus described my invention, what I claim and desire to secure by Letters Patent is—

1. A liquid fuel burner comprising a tubular central body, a feed pipe attached at one end thereof for conveyance of mixed fuel and an atomizing fluid, a plug at the inlet end of the body with diagonal slots, an inner chamber with outlets into the central part and into which the slots discharge from the feed pipe, and a ball confined within the inner chamber and agitated by the fluid flowing therethrough for aiding the atomization of the fuel.

2. An oil burner comprising a central body, an initial mixing and feed pipe attached thereto, inner mixing and grinding chambers at each end of said body, each of said chambers inclosing a loose ball, and having diagonal feed slots for swirling the oil about the ball, and discharge ports from said chambers.

3. An oil burner made of standard pipe fittings, comprising a nipple or central body part, a reducer on the feed end thereof, said nipple being provided with an inner reducer closed at the inner end and forming a bushing with discharge ports, a plug with diagonal slots in the inlet end of the bushing, a ball confined in the bushing and movable by the swirling oil, a reducer on the discharge end of the nipple with slots for oil discharge, a plug closing the outer end of the latter reducer, a diagonally slotted plug at the inlet end of the latter, and a ball in- closed therein.

In testimony whereof I have hereunto set my hand in the presence of two subscribing witnesses.

CHARLES N. MOORE.
